UNITED STATES PATENT OFFICE.

ISAAC T. LEWIS, OF PHILADELPHIA, PENNSYLVANIA.

LOCOMOTIVE SAND-DELIVERING PIPE.

SPECIFICATION forming part of Letters Patent No. 709,414, dated September 16, 1902.

Application filed October 16, 1901. Serial No. 78,886. (No model.)

To all whom it may concern:

Be it known that I, ISAAC T. LEWIS, a citizen of the United States, residing in Philadelphia, Pennsylvania, have invented certain 5 Improvements in Locomotive Sand-Delivery Pipes, of which the following is a specification.

The object of my invention is to provide the lower or delivery end of the track-sand-delivering pipe of a locomotive with means whereby the sand may always be delivered properly upon the track when the locomotive is rounding a curve or in other cases where the delivery-pipe as usually constructed would direct the sand off to one side of the rail instead of upon the top or tread of the same. This object I attain by providing the lower end of the sand-delivery pipe with a laterally-swinging nozzle which may be permitted to 20 assume its proper position by gravity or may be positively controlled from the cab on the engine.

In the accompanying drawings, Figure 1 is a side view illustrating my invention, sufficient of the locomotive being shown in dotted lines to illustrate the application of the invention thereto. Fig. 2 is a plan view. Figs. 3 and 4 are sectional views illustrating the lower end of the sand-delivery pipe with my 30 improved swinging nozzle applied thereto. Fig. 5 is an elevation of the same, and Figs. 6 and 7 are diagrams illustrating the conditions under which my invention is designed to be used.

In Fig. 1 the usual sand-delivery pipes of a locomotive are represented at 1, these pipes being disposed, as usual, so as to deliver sand respectively in front of the forward driver and behind the rear driver. The lower end 40 of the pipe is, however, provided with a fixed nozzle 2, which terminates in a vertical depending portion having opposite projecting studs or trunnions 3, which are in line with the longitudinal wheel-base of the engine, so that the center of each of these nozzles is directly over the center of its corresponding rail when the engine is running upon a straight and level track. A rigid nozzle of this character will, however, fail to 45 properly deliver the sand upon the tread of the rail under certain running conditions. For instance, in rounding a sharp curve the

sand-delivery pipe will be so far out of proper vertical alinement with the center of the rail-tread that it will deliver its sand to one side 55 or the other of said tread, and hence will fail to perform its intended duty. This will be understood on reference to the diagram Fig. 6, in which the dotted curves represent lines of track and the circles represent fixed sand-delivery pipes occupying their ordinary relation to the driving-wheels of the engine. This tendency to deliver the sand to one side or other of the tread of the rail is enhanced by the tilting of the engine, because of the customary rise of the outer rail of the curve, as shown in Fig. 7. This tilting of the engine, and consequently of the sand-delivery pipes, causes the latter to throw the sand outwardly or inwardly instead of in a direct downward 60 course. In order to overcome these objections, I hang upon the trunnions 3 of the fixed nozzle 2 a swinging nozzle 4, which has suitable sockets 5 for the reception of the trunnions 3, accidental displacement of the 65 swinging nozzle 4 being prevented by means of cotter-pins 6 or in any other suitable manner. The natural tendency of the nozzle 4 is therefore always to assume a vertical position, so as to deliver sand directly downward therefrom onto the head of the rail, any lateral deflection of the sand due to the tilting of the 70 engine and sand-delivery pipes being therefore effectually overcome. Where the curve is of very small radius, however, it may be 75 necessary to swing the nozzle 4 inwardly or outwardly beyond the vertical plane, as shown, for instance, by dotted lines in Fig. 5, so as to cause it to deliver sand onto the head of the rail, and I therefore provide means 80 whereby the occupant of the cab can effect the positive adjustment of the swinging nozzle in either direction. These devices are shown in Figs. 1 and 2 and comprise transverse rods 7, each pivoted to projecting lugs 85 9 on swinging nozzles 4, carried by the sand-delivery pipes on opposite sides of the engine, each of these rods 7 being connected by a link 10 to an arm 11 on a longitudinal rock-shaft 12, suitably mounted in bearings on the 90 engine-truck, and having another arm 13, which is connected by a rod 14 to an arm 15 on a rock-shaft 16, having another arm 17 95 projecting up into the cab, so as to be within 100

convenient reach of the engineer or fireman. Hence simultaneous swinging of all of the nozzles to right or left of a central vertical line can be readily effected in accordance with 5 the requirements of the particular piece of track over which the engine is running, so as to cause the delivery of the sand directly onto the treads of the rails under all circumstances.

10 I am aware that sand-pipes of locomotives have been provided with nozzles mounted so as to be swung longitudinally or in a direction parallel with the length of the rail, so as to direct the stream of sand more or less under the driving-wheel; but it will be evident that such nozzles are different from the laterally-swinging nozzles which I employ and are not capable of attaining the object for which my swinging nozzles have been designed. Without claiming broadly, therefore, a locomotive sand-pipe having a swinging delivery-nozzle,

15 I claim and desire to secure by Letters Patent—

20 25 1. The combination of opposite sand-delivery pipes of a locomotive, a transversely-

swinging nozzle at the delivery end of each pipe, a transverse rod connecting said nozzles, a longitudinal rock-shaft having an arm connected to said rod, and connections from said 30 rock-shaft to the cab of the locomotive, substantially as specified.

2. A locomotive sand-pipe curved to conform to the wheel and having secured to its lower end a fixed nozzle with vertical delivery 35 end, and a nozzle mounted thereon so as to swing in a direction transversely to the rail, substantially as specified.

3. The combination of a locomotive sand-pipe with a fixed nozzle secured thereto and 40 having a delivery portion with fore and aft trunnions projecting therefrom and a swinging delivery-nozzle having sockets for the reception of said trunnions, substantially as specified.

45 In testimony whereof I have signed my name to this specification in the presence of two subscribing witnesses.

ISAAC T. LEWIS.
